No. 783,454.

PATENTED FEB. 28, 1905.

J. I. McDONALD.
PRINTING APPARATUS.
APPLICATION FILED APR. 1, 1903.

UNITED STATES PATENT OFFICE.

JOHN I. McDONALD, OF CHICAGO, ILLINOIS.

PRINTING APPARATUS.

SPECIFICATION forming part of Letters Patent No 783,454, dated February 28, 1905.

Application filed April 1, 1903. Serial No. 150,617.

To all whom it may concern:

Be it known that I, JOHN I. McDONALD, a citizen of the United States, residing at Chicago, in the county of Cook and State of Illinois, have invented a certain new and useful Improvement in Printing Apparatus, of which the following is a full, clear, concise, and exact description, reference being had to the accompanying drawings, forming a part of this specification.

My invention relates to the art of printing, and has for its object the provision of an improved construction of instrumentalities employed by compositors and others for setting up forms whereby such instrumentalities may be assorted according to length, the invention having particular utility in connection with leads, spacings, rules, borders, &c. To those familiar with the art of printing it is well known that the devices I have specifically mentioned are redistributed with considerable difficulty after distribution of the type. The work of assorting the leads, spacings, &c., has hitherto been tediously accomplished.

In accordance with my invention I so modify the contour of the leads, spacings, &c., that the selection is more readily effected, there being desirably provided a rack or other means for effecting proper alinement or location of the leads, spacings, &c., and a suitable tool adapted to be engaged with the leads, spacings, &c., to effect their removal from the group in which they have been promiscuously located. The rack is preferably straight, so that the ends of the leads, spacings, &c., that are in engagement therewith will lie in a suitable plane, these leads projecting unequal distances, according to their lengths, away from the rack to be in position to be engaged by the selecting - tool. The longest leads and spacings are selected first, the next in order of length are selected second, the next in order of length selected third, and so on. As the leads, spacings, &c., of each length are selected they are desirably distributed, each with others only of its own length, a very desirable construction being one wherein the rack is provided with an upright portion that has hangers projecting forwardly therefrom upon which the leads or spacings or other similar

material are suspended when the contour of such leads, spacings, &c., is of such a character as to permit of such suspension. In order that the selecting-tool may perform its work, it is of such shape that it will readily engage first with the leads of one length, after the removal of which the said tool is brought into engagement with the leads of another length, and so on. The selecting-tool that may be employed for the purpose is one that is cylindrical, being in one form of the invention in the shape of a slender rod, though I do not wish to be limited to the particular form of selecting-tool that is used. A tool of such a shape as that specifically set forth requires a modification of the contour of the leads, so as to permit of engagement between the leads and the tool, so that the tool may perform its function and effect the removal of the leads. This modification of the contour preferably resides in the formation of recesses in the end portions of the leads, the entrances to which recesses are smaller than the bases thereof, whereby overhanging projections or horns are provided for engagement with the cylindrical or other selecting tool. The rack that engages one end of each of the leads should desirably be of such construction that when the leads are engaged by the selecting - tool they may be removed from the rack after they have been rotated through a sufficient angle by the selecting - tool. When the selecting - tool employed is of such a shape as to require modification in the shape of the leads, the rack is desirably so formed as to engage a modified portion of the contour in a manner to hold the leads in place when they occupy one position and to permit the removal thereof when they are rotated to an alternative position.

In the preferred embodiment of the invention there is located at the middle of each end of each lead or similar device a recess, which recesses are themselves readily alined in the leads of the same length without the exercise of great care. The leads in addition to being engaged at an end of each by the rack are also located with their longitudinal edges in the same planes, so that the free ends of the leads will be so disposed as to bring the recesses in the

edge portions in alinement, whereupon the selecting-tool may be passed into these recesses, as described. Another form of the leads is one wherein the recesses in the ends thereof instead of being circular are dovetail. In another form of the invention the recesses are located at the longitudinal edges of the leads instead of upon the ends, in which case also the recesses are symmetrically disposed, so that it is immaterial how the leads are assembled so long as the recesses are properly alined according to the lengths of the leads.

I will explain my invention more fully by reference to the accompanying drawings, in which—

Figure 1 is a perspective view of the preferred form of my invention. Fig. 2 is a side elevation of a portion of the apparatus illustrated in Fig. 1. Fig. 3 is a view indicating the transfer of selected leads, &c., from the selecting tool or rod to a suspending-pin. Fig. 4 is a view of a modified form of the assembly-rack with a modified form of lead or other suitable device in place thereon. Figs. 5 and 6 are views of modified forms of the leads.

Like parts are indicated by similar characters of reference throughout the different figures.

In the drawings I have illustrated one of several forms of cabinets *a* that may be employed. Upon the horizontal shelf of this cabinet there may be disposed a rib *b*, upon which may be provided an assembly-rack *c*, which may be provided with a retaining-ledge *d*, that may be of any suitable form, such as that shown most clearly in Fig. 2 and Fig. 3.

I have indicated a selecting-tool *e* that is in the form of a cylindrical rod, and where the selecting-tool is of circular cross-section the leads, spacings, rules, or like elements that are to be embraced within my invention are provided with circular recesses or apertures *f* therethrough, these recesses being desirably open at the edges of the leads *g*, so that they may be removed from any portion of the assembly-rack without moving the leads longitudinally of the rack. These holes or apertures are preferably so disposed and shaped that overhanging portions are left at the side edges of the leads, so as to enable the selector to carry the same, as is indicated in dotted lines in Fig. 1 and in full lines in Fig. 3. It is obvious that the recesses *f* may be otherwise shaped and that the selecting-rod may be of other form. In the form of the invention illustrated in Figs. 1 to 4, inclusive, the recesses *f* are located at both ends of each lead or similar device and midway between the longitudinal edges. These leads, &c., are, as is well known, formed in varying lengths to economize material and time, and when they are to be distributed they are assembled upon the rack *d* as they are taken from the pile in which they are pro-

miscuously located, whereafter the selector *e* is brought into engagement with the leads of each length, each group of leads being successively thus engaged by the selector and withdrawn by the movement of the selector, that causes the leads to be inclined with respect to the horizontal shelf of cabinet *a*, whereupon they may be disposed upon the supporting-pins or other suitable support *h*. Fig. 1 indicating the transfer of a group of leads from the selector *e* to a pin *h*. The selector when in the form of a rod circular in cross-section is desirably pointed at one end to facilitate its engagement with the recesses *f*, and the pointed end of the selector is desirably countersunk slightly, as indicated in Fig. 3, so that the sharpened ends of the pin *h* may be engaged by the selector to facilitate the transfer of the leads from the selector to the pins.

It may be desired to protect the leads, &c., and the assembly-rack from wear, for which purpose the said rack may be provided with a protecting-facing, formed, for example, of rubber or other elastic substance *i*, which in the form shown in Fig. 4 also permits the removal of leads from the rack by a longitudinal movement of the leads.

In the form shown in Fig. 5 the shape of the recess *f* has been modified. In the form shown in Fig. 6 the recesses *f* have been located upon the longitudinal edges of the lead; but they are symmetrically arranged, as in the other forms. As indicated in Figs. 5 and 6, the recesses *f* are provided through the leads or the like to modify the contour thereof symmetrically with respect both to a middle line *xx* extending longitudinally of each lead and symmetrically with respect to a middle line *yy* extending transversely of each lead, so that it is immaterial in what manner the leads are gathered together to be placed upon the assembly-rack, because the leads will always be in position to have each size thereof selected by the selector, as the modifications in the contour at the ends of the leads engaged by the selector will be suitably alined for the purpose.

The forms of the invention shown in Figs. 1 to 5, inclusive, where the recesses *f* are located at the transverse edges, midway between the longitudinal edges, are preferred.

It is obvious that changes may be made from the embodiment of the invention herein shown without departing from the spirit of the invention, and I do not, therefore, wish to be limited to the precise characteristics illustrated; but,

Having thus described my invention, I claim as new and desire to secure by Letters Patent—

1. The combination with a plurality of leads, rules or other like printer's article of varying length apertured or recessed at either of their ends midway between their longitudinal edges of a selector-tool adapted to coöp-

erate therewith to effect the removal of leads of a given length, substantially as described.

2. The combination with a plurality of leads, rules or like printer's article of varying length apertured or recessed at either of their ends symmetrically with respect to a middle line extending longitudinally of the lead and with respect to a middle line extending transversely of the lead, of a selector-tool adapted to coöperate therewith to effect the removal of leads of a given length, substantially as described.

3. A plurality of leads, rules or other like printer's article of varying lengths, each apertured or recessed at both ends midway between its longitudinal edges, the apertures or recesses thus formed having entrances smaller than their bases, whereby said articles may be quickly assembled in a single group and separated into smaller groups by a tool that is thereby adapted to select leads or such articles of a similar size at each operation of the tool, substantially as described.

4. A plurality of leads, rules or other like printer's article of varying lengths, each apertured or recessed at both ends symmetrically with respect to a middle line extending longitudinally of the leads and with respect

to a middle line extending transversely of the leads, the apertures or recesses thus formed having entrances smaller than their bases, whereby said leads, &c., may be assembled in a single group and separated into smaller groups by a tool that is thereby adapted to select leads or such articles of a similar size at each operation of the tool, substantially as described.

5. A lead, rule or other like printer's article apertured or recessed at both of its ends midway between its longitudinal edges, the entrances to said recesses being smaller than their bases, substantially as described.

6. A lead, rule or other like printer's article apertured or recessed at both of its ends symmetrically with respect to a middle line extending longitudinally of said article and with respect to a middle line extending transversely of the article, the entrances to said recesses being smaller than their bases, substantially as described.

In witness whereof I hereunto subscribe my name this 24th day of March, A. D. 1903.

JOHN I. McDONALD.
